UNITED STATES PATENT OFFICE.

WILLIAM H. LARAWAY, OF GRAND RAPIDS, MICHIGAN.

VENDING MACHINE.

Application filed August 21, 1920. Serial No. 405,115.

To all whom it may concern:

Be it known that I, WILLIAM H. LARAWAY, a citizen of the United States, residing at Grand Rapids, in the county of Kent and 5 State of Michigan, have invented certain new and useful Improvements in Vending Machines, of which the following is a specification.

My invention relates to improvements in 10 vending machines, and its object is to provide a cheaply made, positively acting vending machine that is not easy of access.

I attain these objects by the mechanism shown in the accompanying drawing, in 15 which Fig. 1 is a front elevation of the machine; Fig. 2 is a sectional elevation of the same on the line 2—2 of Fig. 1. Fig. 3 is a like view of the lower part of the machine upon an enlarged scale. Fig. 4 is a 20 plan of the coin actuated trip, and slides and their supporting element or floor. Fig. 5 is a bottom plan of the same showing the coin discharge slot the entire length of the trip.

Similar reference characters indicate similar parts throughout the several views.

This invention lies principally in the manner of applying and operating the coin controlled mechanism, which is practically as 30 follows: The case 1 is not different from the cases used in many vending machines. It is made with partitions 3, back of the glass front 2, for the reception and free movement 35 of the bottles 23 between the back partition and front partition 3 which form slots or alleyways 8 for the reception of the ends of the bottles.

Below the lower ends of the partitions 3 I make a floor 16 upon which the sliding 40 doors or slides 17 slide freely, and I make a small door 14 back of each sliding door 17 which is held in normal position with a spring 15. Normally this door, or these doors are closed and a bottle is located be- 45 tween its, or their, lower ends and the back edges of the sliding doors 17 so that if the sliding door is forced toward the back of the machine the bottle will force the door 14 open and will drop from between these doors 50 and the slides and into the bottom of the machine, as indicated by their dotted lines in Fig. 3.

I provide for sliding the sliding doors 17 by placing projecting arms 19 upon the up- 55 ward projection 28 of the slide 17, and passing it through the projection 18 on the floor

16 and into the slot opening 11 in the trip 9, back of the retaining plate 21.

The trip 9 is pivotally mounted in the case 1, as at 12, and has a slot 10 the entire length 60 of its lower side for the passage of coin, 24, from its reception slot 11. The coin trip stands, normally, in the position indicated by its dotted lines in Fig. 3 or its solid lines in Fig. 2, where it is held by any available 65 form of spring, as indicated at 13, so that when a coin, as a ten cent piece, is passed through the slot 6 it will pass upon the incline 30 and rest upon the ledge 29 until the trip 9 is thrown over against the floor 16, 70 when the arm 19 will carry the coin 24 in vertical position, as indicated in Fig. 3, which forms a resistance that forces the slide 17 backwardly until a bottle 23 is dropped 75 off of the floor 16, and when the trip is carried back into normal position the coin is released and may drop into the coin receptacle 26, or such other receptacle as may be provided. In this instance I have shown a door 27 for providing access to the coin 80 receptacle.

The actuating rod 12, which forms the pivotal support of the trip 9 passes through the trip supports 22 and has bearings 25 formed thereon, and at the end of one of 85 these bearings I place any available form of handle, as indicated at 5, for manipulating the trip 9 to force the bottles out of the machine, as hereinbefore indicated. In the base 4 I provide a curved chute 20 for the 90 passage of the bottles out of the machine through the opening 7, or its equivalent.

It will be readily understood that many changes may be made in the construction of this machine without departing from the 95 spirit of my invention, as that lies principally in the manner of entering the coin into the trip, of forcing the bottles out of the machine, and of returning the trip into normal position, which is accomplished with the 100 plate 21 drawing upon the head of the arm 19.

Having thus fully described my invention, what I claim as new in the art, is:

1. In a vending machine partitions forming receptacles for goods, doors pivotally connected with certain of said partitions, springs for holding said doors in normal positions, a floor below said door, a sliding actuating element upon said floor, a trip 105 pivotally mounted in the machine at one corner, said trip having a receiving slot 110

formed by an angular bearing at one side and a metal plate at the other side, and a ledge formed at the base of the angular bearing, said trip also having a discharge slot arranged to cooperate with the inclined opening to discharge a coin, and an arm extending from the sliding element into the trip back of the plate so the movements of the trip will actuate the sliding elements.

10 2. In a vending machine, partitions forming slots for the storage of bottles, a door hinged to the lower end of one of the partitions, a spring for holding said door in normal position, a floor below the slot, a

15 sliding element upon the floor below the slot,

a swinging coin actuated trip pivotally mounted in the machine, said trip having a groove in one edge for the discharge of coin, and an opening in the other edge formed by cutting away parts of the trip and forming an inclined receiving surface and a ledge, said opening having a metal covering said covering being slotted for the passage of an arm on the slide, an arm extending backwardly from the slide and engaging the trip to actuate the slide from the movements of the trip.

Signed at Grand Rapids, Michigan, August 17, 1920.

WILLIAM H. LARAWAY.
